UNITED STATES PATENT OFFICE

EDWIN J. SCHWABE, OF FAR ROCKAWAY, NEW YORK

DESIGN FOR A HAND MIRROR

Application filed June 18, 1930. Serial No. 36,086. Term of patent 3½ years.

To all whom it may concern:

Be it known that I, EDWIN J. SCHWABE, a citizen of the United States, residing in Far Rockaway, Long Island, in the county of Queens and State of New York, have invented a new, original, and ornamental Design for a Hand Mirror, of which the following is a specification, reference being had to the accompanying drawing, forming part thereof.

I claim:

The ornamental design for a hand mirror, as shown.

EDWIN J. SCHWABE.
